UNITED STATES PATENT OFFICE.

PETER M. WEGE, OF GRAND RAPIDS, MICHIGAN.

SHEET-METAL SAFE OR CABINET.

1,054,325.

Specification of Letters Patent. Patented Feb. 25, 1913.

Application filed August 16, 1912. Serial No. 715,365.

To all whom it may concern:

Be it known that I, PETER M. WEGE, a citizen of the United States, residing at Grand Rapids, Michigan, have invented certain new and useful Improvements in Sheet-Metal Safes or Cabinets, of which the following is a specification.

This invention relates particularly to improvements in sheet metal safes or cabinets, with sheet metal walls.

While my improvements are particularly available for safes and the like, and I have illustrated the same embodied in a safe structure, the invention may be made use of in double walled structures in various relations.

The main objects of this invention are: First, to provide an improved sheet metal walled structure which is light and simple and economical to produce and is easily and quickly assembled. Second, to provide an improved light sheet metal walled structure which is very rigid. Third, to provide an improved structure of the class described, in which the passage of heat through the wall joints and door joints is quite effectively prevented.

Further objects and objects relating to details and economies of construction and operation will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing, forming a part of this specification, in which:

Figure I is a perspective view of a structure embodying the features of my invention. Fig. II is an enlarged detail horizontal section on a line corresponding to line 2-2 of Fig. I. Fig. III is a detail perspective view on a line corresponding to line 3-3 of Fig. I, one of the doors being partially open. Fig. IV is an enlarged vertical section on a line corresponding to line 4-4 of Fig. I. Fig. V is a detail transverse section on a line corresponding to line 5-5 of Fig. IV. Fig. VI is a detail horizontal section on a line corresponding to line 6-6 of

Fig. I, the lining for the walls being omitted. Fig. VII is a detail vertical section on a line corresponding to line 7-7 of Fig. I. Fig. VIII is a detail perspective view of the wall reinforcing and locking frame 12. Fig. IX is a detail perspective view of the wall reinforcing and locking member 13. Fig. X is an enlarged detail on a line corresponding to line 10-10 of Fig. III, showing details of the door. Fig. XI is a detail section on a line corresponding to line 11-11 of Fig. I. Fig. XII is a detail vertical section on a line corresponding to line 12-12 of Fig. V.

In the drawing, similar numerals of reference refer to similar parts throughout the several views, and the sectional views are taken looking in the direction of the little arrows at the ends of the section lines.

Referring to the drawing, the structure illustrated comprises an outer wall member having a rear wall portion 1, top wall portion 2, and bottom wall portion 3, formed integrally of sheet metal. These walls are provided with out-turned seam members 4 at their edges. The top and bottom wall portions 2 and 3 are provided with angle flanges 5, the arms 6 of these angle flanges being directed rearwardly. The outer side walls 7 are provided with flanges 8 at their top, bottom and rear edges, having seam members 9 coacting with the seam members on the rear, top and bottom walls described. The outer side wall members 7 have angle flanges 10 at their front edges, the arms 11 of these flanges being directed rearwardly as are the arms 6 of the flanges of the top and bottom walls described.

Rectangular frames 12 and 13—see Figs. VIII and IX—are arranged within the walls to reinforce and brace the same and lock the wall seam together. These frames are a tight fit when crowded into place within the walls as shown in the drawing.

In practice, the frames and outer walls are assembled by engaging the seams of one side wall with the seams of the rear top and bottom walls, placing the frames 12 and 13 within the walls thus assembled loosely in a diagonal position, engaging the seams of the other side wall with the rear, top and bottom wall and forcing the frames into place, the rear frame 12 against the rear wall and the front frame 13 into the angle flanges at

the front of the top, bottom and side walls. This locks the wall together and reinforces them so that the walls may be formed of comparatively light sheet metal, and, at the 5 same time, are very rigid and capable of withstanding heavy loads and racking strains.

The rear frame member 12 is formed of angle material arranged with its angles facing forwardly and outwardly. Comparatively light material is satisfactory and I 10 preferably form the same out from heavy sheet metal. The front frame 13 is also of angle material and is arranged in the angle 15 flanges, as stated, and provided with angle extensions 14 which project inwardly beyond the inwardly projecting arms of the wall angle flanges. The upright members of the front frame 13 are provided with arms 20 15 which lie against the front walls. See Fig. VI.

The rear inner wall 17 is provided with flanges 18 at its edges, arranged to embrace the forwardly-projecting arms of the frame 25 12. See Figs. II and IV. The inner side walls 27 are provided with shouldered flanges 28 at their rear edges, which engage the vertical edges of the rear inner wall and clamp the same upon the frame 12 as shown 30 in Fig. II. These side walls are provided with outturned flanges 28' at the top and bottom engaging the top and bottom walls 2 and 3. See Fig. V. The inner side walls 35 are provided with angle flanges 29 at their front edges which are secured to the angle extensions 14 of the front frame by means of the screws 25. See Figs. II and VI. The inner bottom 19 is provided with a shouldered flange 20 at its rear end adapted to 40 engage the lower edge of the rear inner wall and with an angle flange 21 at its front edge which is secured to the extension 14 of the bottom piece of the frame member 13. See Fig. IV. The top inner wall 22 is provided 45 with a shouldered flange 23 at its rear end adapted to engage the upper edge of the rear inner wall and with an angle flange 24 at its front end secured to the angle extension of the top piece of the front frame member 13. 50 See Figs. V and VII. The top and bottom inner walls are forced between the side walls and constitute locking and bracing members. By this arrangement of parts, the walls are simple in form and very easily assembled, and when assembled, the structure 55 is very rigid, although made of light material. Further, a double walled structure is secured which is of very great advantage in safes and structures of light character. The 60 flanges on the inner walls serve as wall spacing members, and also constitute heat insulating elements for the seam joints between the outer side and top and bottom and

rear walls. Owing to the form of the joints, the same being of the interlocking or telescoping seam type, when the walls are expanded by heat as in a fire, considerable movement at the joints is possible without opening the same owing to their telescoping relation. This is a very advantageous feature.

In practice, I preferably close the seam by means of blow pipe welding, but this is mainly to secure the appearance of a solid structure, as it is not an essential for the securing of the parts or making it a rigid structure. The front frame is preferably secured to the wall flanges in which it is arranged, by spot welding. In the structure illustrated, both the inner and outer walls 70 are provided with a lining 30 of asbestos.

The doors 31 and 32 are also chambered or double walled. These doors are formed of sheet metal, the rear edges of the outer walls being turned inwardly or flanged at 33 to 85 form the rear edges of the doors and provided with extensions 34 upon which the inner walls 35 are lapped. At its front edge, the inner wall of the door 31 is provided with a slipped extension 36, while the 90 front edge of the outer wall is lapped over the same at 37 lapping the outer arm of the channel extension of the inner wall. See Figs. III and X. This provides a vertical 95 groove and rib.

The door 32 is of the same construction at its rear edge as that described for the door 31. The front edge of the outer wall of the door is stepped at 38 to coact with the door 31, and is also conformed to provide a channel 39 for the trough 41 containing packing material 43. The door 31 is provided with an A shaped rib 42 adapted to close into the packing material 43. The tops and bottoms of the doors are rabbeted at 50. See 105 Fig. IV.

The door hinges 44 are secured by rivets 45 which are arranged through the walls to engage arms 15 of the front frame member 13, thus forming a rigid support for the 110 doors.

The angle flanges of the top, bottom and side walls coact with the angle extensions of the uprights and top and bottom pieces, to provide packing channels 46 and 47. These 115 packing channels are filled with a suitable fire-proof material, such as asbestos or magnesia. To assist in retaining the packing within the channels, I provide strips 48 which are secured to the wall flanges, as 120 shown in Figs. VI. and VII. By thus arranging the parts, the channels at the tops and bottoms of the doors face forwardly, while the channels at the edges of the doors face inwardly.

The doors are preferably provided with

vertical ribs 49 at their rear edges which close into the packing material. In practice, this packing is put into the channels in a plastic state and the doors closed against it, when it is allowed to set so as to secure a perfect joint.

Casters 51 are secured to the reinforcing bars 52 which are secured to the bottom flanges of the side walls, the caster rivets 52 being arranged therethrough as shown in Fig. XII. The frames 12 and 13 rest upon these reinforcing bars and also the inner side walls so that the weight is distributed so that the walls are not likely to sag or be distorted thereby.

The doors are provided with locks and latches of any suitable form, preferably combination locks, but as these form no part of my present invention, I do not describe the same herein. By this arrangement of parts, I secure a sheet metal walled structure which is strong and rigid, and, at the same time, simple and economical in structure. The structure also effectively withstands heat.

In practice, the inner walls are provided with shelf ledges or other means for supporting the shelves or the like. I have not illustrated the same herein as such supports form no part of the present invention.

While I have shown my improvements as embodied in a safe, they are also adapted for use in various structures, such as sheet metal boxes and the like, where it is desirable to provide a light, rigid metal structure, and one which is simple and economical. A further advantage of my present construction is that by joining the parts as I have shown, a heavy massive appearance is secured which is desirable in a structure of this character.

I have illustrated and described my invention as I have embodied the same in a safe and have accordingly referred to the walls thereof as "rear, top, bottom and side walls". It will be understood, however, that my invention might be embodied in a structure open at the top and in such a structure, the walls corresponding to the top and bottom walls of the structure would become side walls, and the rear wall, strictly speaking, a bottom. I do not, however, wish to be understood as restricting or limiting myself by the use of the terms "top, bottom and rear walls", but have used such terms as a matter of convenience and in the interest of clearness.

I have illustrated and described my improvements in detail in a simple embodiment thereof. I have not attempted to illustrate or describe various modifications possible and which I contemplate, as I believe such modifications will be readily

understood by those skilled in the art from the disclosures herein made. I desire, however, to be understood as claiming my invention specifically in the form illustrated as well as broadly within the scope of the appended claims.

Having thus described my invention, what I claim as new and desire to secure by Letters Patent is:

1. In a structure of the class described, the combination with an outer wall member comprising rear, top and bottom portions provided with seam members at their edges, the front ends of the top and bottom portions being provided with angle flanges, outer side wall members having flanges at their front edges and flanges at their top, bottom and rear edges provided with seam members engaged with the seam members of said top, bottom and rear walls, angle frames arranged within said wall to lock said seam members together, the rear frame being arranged against the rear wall with its angles facing forwardly, the front frame being arranged in said angle flanges of said top, bottom and side walls with its angles facing rearwardly, a rear inner wall having flanges at its edges embracing said rear frame, inner side walls having flanges at the top and bottom engaging the said top and bottom walls and shouldered flanges at their rear edges engaging the inner rear wall, their front edges being secured to said front frame, top and bottom inner walls arranged between said inner side walls and having shouldered flanges at their rear ends engaging said inner rear wall, their front ends being secured to the rearwardly projecting arms of said front frame, and reinforcing members secured to the bottom flanges of the side walls.

2. In a structure of the class described, the combination with an outer wall member comprising rear, top and bottom portions provided with seam members at their edges, the front ends of the top and bottom portions being provided with angle flanges, outer side wall members having angle flanges at their front edges and flanges at their top, bottom and rear edges provided with seam members engaged with the seam members of said top, bottom and rear walls, angle frames arranged within said wall to lock said seam members together, the rear frame being arranged against the rear wall with its angles facing forwardly, the front frame being arranged in said angle flanges of said top, bottom and side walls, with its angles facing rearwardly, a rear inner wall having flanges at its edges embracing said rear frame, inner side walls having shouldered flanges at their rear edges engaging the inner rear wall, their front edges being

secured to said front frame, and top and bottom inner walls arranged between said inner side walls and having shouldered flanges at their rear ends engaging said inner rear wall, their front ends being secured to said angle extensions of said front frame.

3. In a structure of the class described, the combination with an outer wall member comprising rear, top and bottom portions provided with seam members at their edges, the front ends of the top and bottom portions being provided with angle flanges, outer side wall members having angle flanges at their front edges and flanges at their top, bottom and rear edges provided with seam members engaged with the seam members of said top, bottom and rear walls, frames arranged within said wall to lock said seam members together, the rear frame being arranged against the rear wall, the front frame being arranged in said angle flanges of said top, bottom and side walls, a rear inner wall having flanges at its edges embracing said rear frame, inner side walls having flanges at the top and bottom engaging said top and bottom walls and shouldered flanges at their rear edges engaging the inner rear wall, their front edges being secured to said front frame, top and bottom inner walls arranged between said inner side walls and having shouldered flanges at their rear ends engaging said inner rear wall, their front ends being secured to the rearwardly projecting arms of said front frame, and reinforcing members secured to the bottom flanges of the side walls.

4. In a structure of the class described, the combination with an outer wall member comprising rear, top and bottom portions provided with seam members at their edges, the front ends of the top and bottom portions being provided with flanges, outer side wall members having flanges at their front edges, the flanges at their top, bottom and rear edges being provided with seam members engaged with the seam members of said top, bottom and rear walls, frames arranged within said wall to lock said seam members together, the rear frame being arranged against the rear wall, the front frame being arranged in said flanges of said top, bottom and side walls, a rear inner wall having flanges at its edges embracing said rear frame, inner side walls having shouldered flanges at their edges engaging the inner rear wall, their front edges being secured to said front frame, and top and bottom inner walls arranged between said inner side walls and having shouldered flanges at their ends engaging said inner rear wall, their front ends being secured to the rearwardly projecting arms of said front frame.

5. In a structure of the class described,

the combination of an outer wall member comprising rear, top and bottom wall portions provided with seam members at their edges; outer side wall members provided with seam members engaged with the seam members of said top, bottom and rear walls; frames arranged within said walls to reinforce the same and lock said seam members together; an inner rear wall; and inner top, bottom and side walls having their rear ends engaged with said rear frame, their front ends being secured to said front frame.

6. In a structure of the class described, the combination of an outer wall member comprising rear, top and bottom wall portions provided with seam members at their edges; outer side wall members provided with seam members engaged with the seam members of said top, bottom and rear walls; an angle frame arranged within said walls to reinforce the same and lock said seam members together, said frame being arranged against the rear wall with its angles facing forwardly and outwardly; an inner rear wall arranged on the forwardly-projecting arms of said frame; inner top and bottom walls having shouldered spacing flanges at their rear ends engaging said frame; and inner side walls having shouldered spacing flanges at their rear edges engaging said frame.

7. In a structure of the class described, the combination of an outer wall member comprising rear, top and bottom wall portions provided with seam members at their edges; outer side wall members provided with seam members engaged with the seam members of said top, bottom and rear walls; a frame arranged within said walls to reinforce the same and lock said seam members together; an inner rear wall arranged on said frame; and inner top, bottom and side walls engaging said frame.

8. In a structure of the class described, the combination of an outer wall member comprising a rear wall and opposed side wall portions provided with seam members at their edges, opposed side wall members having seam members engaged with the seam members of said wall member, an angle frame arranged within said walls to reinforce and lock said seam members together, said frame being arranged against the rear wall with its angle facing forwardly and outwardly, an inner rear wall arranged on the forwardly-projecting arms of said frame, and inner side walls engaged with said frame.

9. In a structure of the class described, the combination of an outer wall member comprising a rear wall portion and opposed side wall portions provided with seam members at their edges, opposed outer side wall

members provided with seam members engaging the seam members of said wall member, a rectangular frame arranged within said walls to reinforce the same and lock 5 said seam members together, an inner rear wall supported by said frame, and inner side walls having shoulder flanges at their rear edges engaging said frame.

10. In a structure of the class described, the combination of a wall member comprising rear, top and bottom wall portions provided with seam members at their edges and angle flanges at their front ends; side wall members having seam members engaged with 15 the seam members of said top, bottom and rear walls and angle flanges at their front edges; and rectangular frame members arranged within said walls to lock said seam members together, the front frame member being 20 arranged in the angle flanges of said top, bottom and side walls, all coacting for the purpose specified.

11. In a structure of the class described, the combination of a wall member comprising rear, top and bottom wall portions provided with seam members at their edges and flanges at their front ends; side wall members having seam members engaged with the seam members of the top, bottom and rear 30 walls; and rectangular frames arranged within said walls to lock said seam members together, one of said frame members being arranged within the flanges of the top and bottom walls, all coacting for the purpose 35 specified.

12. In a structure of the class described, the combination of a wall member comprising rear, top and bottom wall portions provided with seam members at their edges; side wall members having seam members to engage with the seam members of said top, bottom and rear walls and flanges at their front edges; and rectangular frames arranged within said walls to lock said seam members 45 together, all coacting for the purpose specified.

13. In a structure of the class described, the combination of a wall member comprising rear, top and bottom wall portions provided with seam members at their edges and flanges at their front ends; side wall members having seam members interlocking with the seam members of said top, bottom and rear walls; and a frame member arranged within the flanges of the top and bottom walls to engage the side walls to lock the seam members in engagement, all coacting for the purpose specified.

14. In a structure of the class described, the combination of a wall member comprising rear, top and bottom wall portions provided with seam members at their edges and angle flanges at their front ends, side wall

members having seam members interlocking with the seam members of said top, bottom 65 and rear walls, and angle flanges at their front edges, and a rectangular frame member arranged within said angle flanges of said top, bottom and side walls to lock the seam members in engagement, all coacting 70 for the purpose specified.

15. In a structure of the class described, the combination of a wall member comprising rear, top and bottom wall portions provided with seam members at their edges and flanges at their front ends, side wall members having seam members interlocking with the seam members of said top, bottom and rear walls, and flanges at their front edges, and a rectangular frame member arranged 75 within said flanges of said top, bottom and side walls to lock the seam members in engagement, all coacting for the purpose specified.

16. In a structure of the class described, the combination of a wall member comprising a rear wall portion and opposed side wall portions provided with seam members at their edges; opposed side walls having flanges provided with seam members interlocking with the seam members of said wall member, and a frame arranged within said walls to reinforce the same and lock said seam members together.

17. In a structure of the class described, the combination of a wall member comprising rear and opposed side wall portions provided with seam members at their edges, opposed side wall members provided with seam members interlocking with the seam members of said wall member, and a frame arranged within said walls to reinforce the same and lock said seam members together.

18. In a structure of the class described, the combination of an outer wall member comprising top, bottom and rear wall portions provided with seam members at their edges, the front ends of the top and bottom portions being provided with flanges, outer side wall members having flanges at their 110 edges, the flanges at the top, bottom and rear edges being provided with seam members engaged with the seam members of said bottom and rear walls; reinforcing members arranged within the flanges at the bottom of 115 the said side wall members, frames arranged within said wall to lock said seam members together, the rear frame being arranged against the rear wall, the front frame being arranged in the flanges at the front edges 120 of said top, bottom and side walls, said frames being disposed to rest on said reinforcing members, a rear inner wall arranged on the rear frame, inner side walls having bottom flanges resting on said reinforcing 125 members, the upper ends of said side walls

being in engagement with the top, the rear edges of said side walls being in engagement with said rear wall, their front edges being secured to the front frame, and inner 5 top and bottom walls arranged between said side walls engaging said rear inner wall, their front ends being secured to said front frame.

19. In a structure of the class described, 10 the combination of an outer wall member comprising top, bottom and rear wall portions provided with seam members at their edges, the front ends of the top and bottom portions being provided with flanges, outer 15 side wall members having flanges at their edges, the flanges at the top, bottom and rear edges being provided with seam members engaged with the seam members of said bottom and rear walls, reinforcing members 20 arranged within the flanges at the bottom of the said side wall members, and frames arranged within said wall to lock said seam members together, the rear frame being arranged against the rear wall, the front frame 25 being arranged in the flanges at the front edges of the top, bottom and side walls, said frames being disposed to rest on said reinforcing members.

20. In a structure of the class described, 30 the combination of an outer wall member comprising top, bottom and rear wall portions provided with seam members at their edges, outer side wall members having flanges at their top, bottom and rear edges 35 provided with seam members engaged with the seam members of said bottom and rear walls, reinforcing members arranged within the flanges at the bottom of the said side wall members, frames arranged within said 40 wall to lock said seam members together, said frames being disposed to rest on said reinforcing members, a rear inner wall, inner side walls having bottom flanges resting on the said reinforcing members, the upper ends of said side walls being in engagement with the top, their rear edges being in engagement with said rear wall, their front edges being secured to the front frame, and inner top and bottom walls arranged 45 50 between said side walls engaging said rear inner wall, their front ends being secured to the front frame.

21. In a structure of the class described, the combination of an outer wall member 55 comprising top, bottom and rear wall portions provided with seam members at their edges, outer side wall members having flanges at their top, bottom and rear edges provided with seam members engaged with the seam members of said bottom and rear walls, reinforcing members arranged within the flanges at the bottom of the said side wall members; and frames arranged within

said wall to lock said seam members together, said frames being disposed to rest 65 on said reinforcing members.

22. In a structure of the class described, the combination of the outer top, bottom and side walls having angle flanges at their front edges; an angle frame arranged in 70 said flanges, the rearwardly-projecting arms of said frame being provided with angle extensions; inner walls having angle flanges secured to said angle extensions of said frame; strips secured to said inner wall 75 flanges to coat therewith and with the angle extensions of said frame to provide packing channels; and a pair of doors having ribs on their rear edges arranged to close against the packing in the vertical 80 channels, said doors being rabbeted at the top and bottom to overlap the packing in the channels at the top and bottom of the doors.

23. In a structure of the class described, 85 the combination of the outer top, bottom and side walls having flanges at their front edges; an angle frame arranged in said flanges with its angles facing rearwardly, the rearwardly-projecting arms of said 90 frame being provided with angle extensions; inner walls having angle flanges secured to said angle extensions of said upright and top and bottom pieces; strips secured to said 95 inner wall flanges to coat therewith and with the angle extensions of said uprights and top and bottom pieces to provide packing channels about the door openings; and packing arranged in said channels.

24. In a structure of the class described, 100 the combination with the outer top, bottom and side walls; an angle frame arranged in said walls with its angles facing rearwardly, the rearwardly-projecting arms of said 105 frame being provided with angle extensions; inner walls having angle flanges secured to said angle extensions of said frame and co-acting therewith to provide packing channels about the door opening; packing arranged in said channels; and a pair of doors 110 having ribs on their edges arranged to close against the packing in the vertical channels and being rabbeted at the top and bottom to overlap the packing in the channels at the top and bottom of the door. 115

25. In a structure of the class described, the combination with the outer top, bottom and side walls; an angle frame arranged in said walls with the angles facing rearwardly, the rearwardly-projecting arms of 120 said frame being provided with angle extensions; inner walls having angle flanges secured to said angle extensions and co-acting therewith to provide channels about the door opening; and packing arranged in said 125 channels.

26. A structure of the class described provided with a door opening having packing channels about the same, the channels at the top and bottom of the door opening facing forwardly, the channels at the sides of the door opening facing inwardly; packing arranged in said channels; and doors having ribs on their rear edges arranged to close against the packing at the sides of the door, the top and bottom of the door being rab-

beted to close against the packing in the channels at the top and bottom of the door opening.

In witness whereof, I have hereunto set my hand and seal in the presence of two ¹⁵ witnesses.

PETER M. WEGE. [L.S.]
